EDWIN L. HARMON, OF GROTON, NEW YORK, ASSIGNOR TO L. C. SMITH & CORONA TYPE-WRITERS, INC., OF SYRACUSE, NEW YORK, A CORPORATION OF NEW YORK

TYPEWRITING MACHINE

Application filed September 25, 1928. Serial No. 308,157.

This invention relates to improvements in typewriting machines and more particularly to the provisions for holding paper sheets, envelopes, etc. in proper relation to the platen for receiving impressions from the types.

The invention has for its principal objects to provide simple and efficient means for guiding the work sheets over the printing line from the paper feed roll mechanism; to provide work-retaining and guiding means comprising a shiftable work-holding member adapted to normally hold work pieces of various widths to the platen where they cross the printing line and prevent the leading portions thereof falling forward; and simple and efficient means for holding said member in "on" and "off" positions; to provide work feeding and guiding means comprising a work-piece holder shiftable into and out of work-holding relation with the platen, and platen-rotating line-spacing means adapted to effect restoration of said holder to holding position if actuated while the holder is in "off" position; to provide an improved means for yieldably holding a pivoted paper-retaining bail both in and out of paper retaining relation with a platen; and to provide a paper bail and a combined carriage returning and platen rotating line spacing device correlated to restore the bail to paper holding position by actuation of said device.

Other objects and advantages of the invention will appear from the following description of the preferred embodiment of the invention illustrated in the accompanying drawings, in which

Figure 1 is a plan view of the platen carriage and carriage bed of a three-quarter strike typewriting machine in which the improvements are embodied;

Fig. 2 a side elevation of the parts shown in Fig. 1 with the left hand finger wheel broken away, showing the line space lever at the limit of its platen rotating throw and the paper-retaining bail approaching its paper retaining position from its "off" position from which it has been released and shifted by the operating stroke of the lever;

Fig. 3 a section on the line 3-3 of Fig. 1;

Fig. 4 an enlarged sectional view on the line 4-4 of Fig. 5;

Fig. 5 an enlarged sectional view on the line 5-5 of Fig. 1;

Fig. 6 a view similar to Fig. 5, showing the bail locked in "off" position;

Fig. 7 an enlarged sectional view on the line 7-7 of Fig. 1, the "off" position of the bail being indicated in dotted lines; and

Fig. 8 a perspective view of the bail.

The improvements have been illustrated in connection with the Corona three-quarters strike, four bank, portable typewriting machine but it will be obvious that the invention may be embodied in other styles of machines and that various changes in the details of construction and arrangement of the parts may be made without departing from the scope and spirit of the invention.

The rearwardly tilted, sheet metal, platen carriage 10 of the Corona machine is mounted on a rearwardly tilted, sheet-metal carriage bed 11, suitable anti-friction bearings 12 being interposed between the carriage and bed. The carriage is provided with a feed rack 13 through which it is fed step by step from right to left for letter spacing by the escapement mechanism, not shown. The carriage is returned and the platen simultaneously rotated for line spacing through the medium of a carriage-returning and line-spacing hand lever 14 pivotally mounted on the carriage.

The carriage is provided with sheet metal end plates 15 and 16 formed with integral tubular bearing bosses 17 and 18 for the shaft 19 of the platen 20.

A finger wheel 21 is locked by a suitable set screw 26 on the right hand end of the platen shaft, and a finger wheel 22 is fixed on a sliding sleeve 23 on the platen shaft at the left hand end of the shaft, said sleeve extending through bearing boss 18 and hub 24 of a line-spaced ratchet wheel 25 into the platen for operating a suitable clutch to lock the ratchet wheel to the platen and unlock it therefrom for fractional line-spacing. The platen hub 27 at the right hand end of the platen is locked to platen shaft 19 by a set screw 28 and the outer end of said hub abuts

60

the inner end of portion 17^a of boss 17, while the outwardly projecting, reduced, end portion of hub 24 of the ratchet wheel 25 abuts the inner end of boss 18.

6 The line space lever 14 has a yoke-like fulcrum portion 29, the horizontal superposed arms of which are pivotally and slidably mounted on a vertical post 30 held in superposed ears 31 and 32 of a sheet metal bracket 33 which is fastened to the outer face of end plate 16 by screws 34. A spring 35 connects yoke 29 of lever 14 with bracket 33 and tends to swing the forwardly extending handle portion of the lever to the left into 10 the position shown in Fig. 1 and draw the yoke portion of the lever down the post to different levels determined by the setting of the line space regulating lever 36. This lever 36 is pivoted on end plate 16 at 37 and has a rearwardly extending handle and locking arm which is laterally springy and carries a locking stud 38 adapted to be engaged in either of two apertures 39 and 40, as shown in Figs. 2 and 7, to position the 15 forward stop arm of the lever at different levels under the upper arm of the line space lever yoke.

When regulator 36 is set as in Fig. 7 the rigid, inwardly extending, line-space pawl 41 on the upper arm of the lever yoke is adapted to rotate the ratchet wheel a single line space, and when set as in Fig. 2 is adapted to engage the wheel one tooth further down and rotate the wheel a double space, 20 before the inward swinging and upward sliding movements of the line space lever are stopped, respectively, by engagement of the edge 42 of the upper yoke arm with stop lug 43 on end plate 16 and engagement of the lower yoke arm with the under side of a stop shoulder 44 formed on post 30, as shown in Fig. 2. The outward swinging of lever 14 is limited by engagement of a stop extension 45 of the lower yoke arm with the outer 25 face of bracket 33. The lever thus has a fixed pivotal throw and a variable sliding throw, and always stands in the same position at the end of its line-spacing stroke.

A stationary, combined paper guide, printing line indicator and printing point indicator 46 is rigidly clamped at its lower end to a sheet metal bracket 47 which is rigidly held to the carriage bed midway the ends of the bed by a pair of screws 48 which are 30 aligned longitudinally of the bed, and one of which is shown in Fig. 3. Member 46 is formed of resilient sheet metal so as to be slightly flexible and is clamped to bracket 47 by an angular clamping member 49 and a pair of screws 50 which extend through upturned forward portions of bracket 47 and the lower end of member 46 and are threaded into the upturned forward portions of member 49. Member 46 is formed with horizontal wings 51, the upper edges of which ex-

tend along the printing line of the platen, and said member is provided with an opening 52 through which the types on the type bars 53 of the machine strike to the printing point, the upper portion of said member between 70 the wings consisting of an inverted V-shaped bar 46^a extending above the wings, the apex of which bar indicates the location of a vertical line through the printing point.

The foregoing parts are all constructed 75 substantially as in the Corona machine above referred to, and said machine is provided with a paper feed mechanism for feeding and guiding the work pieces downwardly behind the platen, under the platen, and up in front of the platen behind member 46 which then directs the paper upwardly and rearwardly over the upper front portion of the platen. The paper feeding and guiding means just referred to is constructed substantially as 80 shown in the patent to Armstrong, No. 1,619,-013, dated March 1, 1927, but it will be obvious that any other suitable feeding and guiding means may be employed.

In said patent a paper retaining bail device is shown, and the objects of the present invention include the provision of an improved paper bail mechanism whereby the insertion of sheets in the machine and making of erasures are facilitated, improved 95 means for holding the bail in "on" and "off" positions, simple and efficient means for limiting the throw of the bail in both directions, and means whereby the bail will be restored, if left accidentally in "off" position, by the 100 operation of the carriage returning and line-spacing lever, such operation of the lever being almost invariably performed before starting of writing on an inserted sheet. It is, of course, impossible for the operator to type to any great extent after any throw-off of the bail without actuating the line spacing mechanism, so that by the arrangement set forth the bail will be restored before or shortly after starting of typing. The improvements as shown associated with the foregoing 105 described parts of the Corona machine will now be described.

The paper bail is preferably formed of a single piece of sheet metal, as shown, and consists of a combined letter-space scale and paper-holding and guiding cross-bar 54, and a pair of side arms 55 and 56 having aligned bearing holes 57 for the shoulder portions of pivot screws 58. The side arms lie flatwise in vertical fore and aft extending planes and pivot screws 58 hold the arms to the end plates 15 and 16, of the carriage at the inner faces of the end plates for swinging movements of the bail about an axis which is parallel with the axis of the platen and preferably, as shown, is below the level of the printing line and slightly above the level of the axis of the platen. Side arm 56 is formed with an integral extension 59 at the oppo- 125 130

site side of its pivot hole from the cross-bar 54, and said extension 59 is provided at its forward edge at its lower end with an inwardly projecting integral lug 60 preferably having an open slot 61 extending upward from its lower edge, as shown. The side arms of the bail are preferably provided with concave edge portions 55^a and 56^a, respectively, which engage the reduced outwardly projecting portion of hub 24 of ratchet wheel 25 and the larger outer end portion of boss 17, respectively, to positively limit the extent of rearward swinging movement of the bail and hold cross bar 54 slightly out of contact with the platen when the bail is in "on" position, as shown in Figs. 1, 3, 4, 5 and 7.

The crossbar is preferably provided with letter-space scale graduations and figures on its outer face, and is preferably cocked relatively to the direction of length of the side arms so as to lie flatwise in an upwardly and rearwardly inclined plane, as shown, when the bail is in "on" position, so that the scale is readily visible to the operator and so that the paper sheets or other work pieces will be guided upward and rearward over the top of the platen by the flat under face of the crossbar. The length of the side arms is such that the crossbar in the "on" position of the bail extends along the platen parallel therewith above the printing line and out of the paths of movement of the heads of the type bars 53 of the machine, preferably overlying the top of the platen, as shown. The portion 46^a of guide member 46 extends over the upper front portion of the platen to a point closely adjacent the forward edge of crossbar 54 of the bail and is curved to conform substantially with the curvature of the platen and is slightly flexible to allow feeding of thick work sheets, or the employment of several sheets in manifolding work.

The bail is adapted to be manually swung forward to an "off" position in which its crossbar is shifted a substantial distance away from the platen to facilitate the introduction of work sheets into the machine, and also to facilitate making of erasures, particularly on carbon copies. In the machine shown the bail swings to the "off" position shown in Fig. 6 and in dotted lines in Fig. 7, the crossbar of the bail swinging forward and slightly upward away from the platen to a point in a vertical plane passing in front of the platen. In the "off" position the bail crossbar is out of the path of the type bar heads and above and forward of the upper end 46^a of the guide 46 so that sheets introduced into the machine while the bail is in "off" position will be directed upward and rearward under the bail crossbar and will be caught and held to the platen by the crossbar when the bail is restored to its "on" position. The bail may be readily pushed rearward from its "off" position by finger pressure on the grad-

uated face of the crossbar, and side arm 56 is provided with an integral flat lug 62 extending inward from the rear edge of the arm perpendicular to crossbar 54 and abutting at its upper end to rear edge of the crossbar, thus affording a convenient finger piece for drawing the bail into its "off" position.

The bail, in the preferred construction shown, is yieldably held in both its "on" and "off" positions through the medium of a spring 63 and a lever 64, said lever having a stop portion for positively limiting the extent of throw-off movement of the bail, and the spring being connected with both the bail and lever and holding the lever and the downward extension of side arm 56 in contact with each other. Lever 64 is preferably formed of a flat piece of sheet metal and pivoted at its rear end on the reduced, cylindrical, shaft-bearing, inner end portion 17^a of boss 17 on end plate 15 of the carriage, being confined between the outer end of platen hub 27 and the inner end of the enlarged portion of the boss and extending forward flatwise in a vertical plane with its forward portion extending through slot 61 in contact lug 60 of the downward extension 59 of bail side arm 56. The lever is thus held by the side walls of slot 61 and by the opposed portions of hub 27 and boss 17 against lateral movement and accidental disconnection from the bail. The arrangement just described affords a simple, economical and efficient mounting of the lever and shifting contact connection between the lever and bail.

Lever 64 is preferably provided with a combined bail stop and spring anchor lug 65 which extends upward from the upper edge of said lever about midway its ends intermediate the vertical planes of the lever and bail axes. Spring 63 is a helical tension spring and its lower hook end is engaged in an aperture in the upper end of lug 65, the upper end of said spring being attached to the bail above the pivotal axis of the bail, preferably by engagement of its upper hook end in an eye 66 formed by stamping inward a strip of metal from the upper portion of side arm 56.

Lever 64 extends forward from stop lug 65 under the axis of the bail from a point materially in rear of the vertical plane of said axis to a point materially forward of said plane, and the stops 17 and 24 coact with stop edge portions 56^a and 55^a of the bail to arrest rearward swinging of the bail at the "on" position shown in Fig. 5 with contact lug 60 of the downward bail extension 59 engaged over the upper edge of the lever at the forward end of the lever at a point in a vertical plane forward of the vertical plane of the bail axis, while stop 65 coacts with lug 60 to arrest forward swinging of the bail at the "off" position shown in Fig. 6 with lug 60 engaged over the upper edge of the lever at a

point in a vertical plane in rear of the vertical plane of the bail axis.

The described arrangement is such that force transmitted from the spring to the downward bail extension is exerted in a direction tending to urge the crossbar of the bail toward the platen while the bail is in "on" position, and is exerted in a direction tending to urge the crossbar of the bail away from the platen while the bail is in "off" position, the change in direction of force taking place approximately as the contact edge of lug 60 passes under the bail axis. Spring 63 exerts force directly on the bail at its upper end tending to urge the crossbar of the bail toward the platen while the bail is in "on" position, and, preferably, stop 65 is so located (as shown) that the direct application of force by the spring to the bail is always exerted in said direction, the opposing directly applied and indirectly applied spring forces neutralizing each other in the "off" position of the bail. This arrangement affords a compact structure giving ample access to the work for making erasures, easy work introduction, and a yielding lock-off of the bail, without an excessive swinging of the bail carrying the crossbar into the path of the type bar heads which would be liable to result in injury to the type faces and bar if keys are struck while the bail is in "off" position.

The opposed spring forces and the friction between the lug 60 and lever 64 yieldably hold or lock the bail in "off" position. Preferably, however, the upper edge of the lever is formed with a cam hump 67 immediately forward of lug 65 forming a locking notch adapted to receive the lug 60 when the bail is rocked to "off" position. The forward edge of lug 65 forms an abrupt rear wall of said notch engageable by the rear face of lug 60 to positively arrest throw-off movement of the bail, while the rear slope of the cam hump 67 forms a sloping cam forward wall of the notch permitting the bail to be forced back by finger pressure on the crossbar sufficiently to release the bail for a spring snap restoring movement but offering a substantial resistance to bail release reducing liability of accidental return of the bail to "on" position.

The high point of cam 67 is preferably located under the bail axis at the point where the direction of spring force transmitted to the bail by the lever changes, as shown. The cam hump also preferably terminates materially short of the limit of outward movement of lug 60 along the lever 64, and the outer upper edge portion of the lever and the bottom of the locking notch in both extreme positions of the bail preferably lie in the arc of a circle struck from the bail axis, as shown. The described arrangement permits relatively easy yielding movement of the bail bar away from the platen through a lim-

ited range to better accommodate varying numbers of superposed work sheets and gives a quick impulse to the bail in restoring direction from the cam as soon as the direction of force from the lever to the bail is changed by a manual rearward thrust on the crossbar. The rear cam edge of the hump 67 also acts to urge lug 60 against stop lug 65 in throw-off operations of the bail.

The action of the line-space mechanism to restore the bail if the bail be inadvertently left in "off" position will now be described, with particular reference to Figs. 1, 2 and 7. From the description of the line-space mechanism heretofore given, it will be seen that the rigid pawl 41 on the operating stroke of lever 14 swings rearward and slides slightly upward respectively about and along bearing post 30 of the lever and always moves to the same position irrespective of the setting of the regulator 36, the final position of the parts at the end of a line spacing and carriage returning stroke of the lever being shown in Fig. 2. When the bail is in "off" position side arm 55 thereof has an upstanding forward edge portion 55^b extending upward across the path of movement of pawl 41 in all settings of the regular well forward of the limit of rearward movement of the rear edge of the pawl, as shown in Fig. 7. When lever 14 is swung toward the right on its operating stroke pawl 41 engages edge 55^b of bail side arm 55 and rocks the bail to the position shown in Fig. 2, fully releasing the bail by moving lug 60 forward past the apex of cam hump 67 so that the bail will snap to full "on" position under the action of spring 63.

What I claim is:

1. In a typewriting machine, the combination with the platen, of a paper guiding means associated with the platen and movable out of paper guiding relation therewith, and line spacing mechanism for rotating the platen adapted to restore said paper guiding means to effective position upon actuation of said line spacing means.

2. In a typewriting machine, the combination of a traveling platen carriage, a platen rotatably mounted on the carriage, line-spacing means for rotating the platen and returning the carriage, a paper guide shiftably mounted on the carriage and having a portion extending longitudinally of the platen and of a length corresponding substantially with the length of the platen, said guide being shiftable to move said longitudinally extending portion thereof toward and from the platen, and means for yieldably holding said guide in either of two shifted positions in one of which said longitudinal portion thereof lies close to the platen, said line-spacing and carriage returning means having a part thereof cooperative with said guide to cause the same to shift to said last-mentioned posi-

- tion upon an actuation of the line-spacing and carriage returning means while the guide is held in its other shifted position.
3. In a typewriting machine, the combination of a platen carriage, a platen journaled on the carriage, a paper bail cooperative with the platen and pivoted on the carriage for movement out of operative relation with the platen, means for holding said bail in inoperative position, and a carriage returning and platen line-spacing device for releasing said bail upon an actuation of said device with the bail in inoperative position.
4. In a visible writing typewriting machine, the combination with the carriage and platen, of a paper retaining bail pivoted on the carriage to swing forwardly away from the platen and rearwardly toward the platen, means cooperative with said bail to yieldably hold the same in forwardly displaced "off" position and to restore the bail to paper-retaining position upon a partial rearward movement of the bail from "off" position, and a combined carriage returning and line-spacing device engageable with said bail to effect such partial rearward movement of the bail from "off" position upon an actuation of the device with the bail in "off" position.
5. In a typewriting machine having a traveling platen carriage and a rotatable platen journaled on the carriage, the combination of a line-spacing member pivoted on the carriage to swing about an axis extending transversely of the platen, and a paper retaining bail pivoted on the carriage to swing about an axis extending longitudinally of the platen to an "off" position in which one side arm of the bail is in the path of movement of said swinging line-spacing member and is removable thereby to restore the bail to paper-returning position.
6. In a typewriting machine, the combination of a platen, a pawl and ratchet mechanism for rotating the platen for line-spacing, a paper retaining device spring urged into cooperative relation with the platen and shiftable to an in-operative position in which it is yieldably locked against restoration to paper-retaining position, said pawl being shiftable during platen-rotating strokes thereof in a path for engaging and releasing said device.
7. In a typewriting machine, the combination of a platen, a platen carriage having end plates formed with inwardly projecting tubular bearing bosses for the platen shaft, one of said bosses having a reduced cylindrical inner end portion and the platen having a hub portion of larger diameter abutting said end portion, a paper retaining bail having its side arms pivotally held to said end plates, and a spring urged lever pivoted on said reduced cylindrical boss portion and cooperative with the adjacent side arm of the bail to yieldably lock the bail in "off" position.
8. In a typewriting machine, the combination of a platen carriage having end plates, a platen journaled in the carriage end plates, one of said end plates having an inwardly extending bearing boss for the platen shaft having a reduced cylindrical inner end portion, a paper retaining bail having side arms pivotally held to the carriage end plates, one of said side arms engaging said bearing boss between the adjacent end plate and said reduced inner end portion of the boss to hold the crossbar of the bail slightly spaced from the platen in the "on" position of the bail, and a spring urged lever pivoted on said reduced boss portion and cooperative with the adjacent bail side arm to yieldably lock the bail in "off" position.
9. In a typewriting machine, the combination of a platen carriage having end plates, a platen journaled in the carriage end plates, one of said end plates having an inwardly extending bearing boss for the platen shaft having a reduced cylindrical inner end portion, a paper retaining bail having side arms pivotally held to the carriage end plates, one of said side arms engaging said bearing boss between the adjacent end plate and said reduced inner end portion of the boss to hold the crossbar of the bail slightly spaced from the platen in the "on" position of the bail, and a spring urged lever pivoted on said reduced boss portion and cooperative with the adjacent bail side arm to yieldably lock the bail in "off" position.
10. In a typewriting machine, the combination of a platen carriage having end plates, a platen journaled in the end plates, a line-space ratchet wheel held to the platen at one end of the platen and having a hub portion extending outward toward the adjacent carriage end plate, the carriage end plate at the opposite end of the platen from said ratchet wheel having an inwardly extending bearing boss for the platen shaft, a paper retaining bail having its side arms pivotally held to the end plates and engageable with said boss and ratchet wheel hub to determine the "on" position of the bail; and a spring urged locking lever pivoted on said bearing boss and cooperative with the adjacent side arm of the bail to determine the "off" position of the bail and yieldably hold the bail in said predetermined "off" position.
11. In a typewriting machine, the combination of a platen, a paper retaining bail, a lever pivoted to swing about an axis parallel with the bail axis, and helical tension spring connected at its opposite ends with the lever and bail holding the lever in yielding engagement with the bail at the opposite side of the bail axis from the bail crossbar and normally urging the bail toward the platen.

into paper retaining position, said lever having a locking notch in its bail engaging surface into which the lever engaging portion of the bail is shiftable upon manual swinging 5 of the bail out of paper retaining position to releasably lock the bail in "off" position.

12. In a typewriting machine, a paper bail mounted to swing about a fixed axis to and from paper guiding position, a pivoted bail- 10 swinging arm mounted to swing about a fixed axis parallel with the bail axis, means carried by the bail to swing bodily therewith at the opposite side of the bail axis from the bail cross bar and having a traveling engagement 15 with said arm toward and from the arm axis past a point on the arm at which said bail and arm are on a dead center, a bail-driving power spring constantly urging the arm in the same direction about its axis against said 20 bail-carried means throughout the throw of the bail, and means for automatically arresting movement of the bail under pressure of said arm away from paper guiding position. 25

13. A typewriting machine as claimed in claim 12, wherein said spring is connected at its opposite ends with the bail and arm, the points of connection being located to afford a direct pull of the spring on the bail throughout the limits of bail throw in a direction urging the bail toward paper guiding position.

14. A typewriting machine as claimed in claim 12, wherein the arm surface over which said bail-carried means travels has a cam hump intermediate its ends extending nearer the bail axis than the end portions of said surface and on the high point of which said bail-carried means is engaged in the dead center relation of the bail and arm. 35

15. A typewriting machine as claimed in claim 12, wherein means are provided for positively limiting movement of the bail toward paper guiding position, and the arm surface upon which said bail-carried means travels has an intermediate portion rising toward the bail axis and end portions, that end portion of the arm surface engaged by said means in the paper guiding position of the bail being concentric with the bail axis when 40 the bail is in guiding position and the hump being located to permit a limited travel of the bail-carried means over said concentric surface portion before the bail reaches the maximum limit of its movement toward paper guiding position. 55

16. A typewriting machine as claimed in claim 12, wherein the spring is a helical tension spring connected at its opposite ends to the arm and bail, the connection to the 60 bail being at the side of the bail axis at which the cross-bar of the bail is located and the connection with the arm being between the arm axis and the bail-carried means engaging portion of the arm, and said points of 65 connection being so located that the arrest of

the swinging of the bail away from paper guiding position occurs before the spring reaches the axial line about which the bail swings. 70

17. A typewriting machine as claimed in claim 12, wherein the spring is a helical tension spring connected at one end with the bail at the cross-bar side of the bail axis and connected at its opposite end with the arm at a point between the axes of the arm and bail 75 and close to the bail axis, and wherein said means for automatically arresting swinging of the bail away from paper guiding position arrests the bail before the spring reaches the axial line about which the bail swings. 80

18. In a typewriting machine, the combination with a platen and a manually shiftable paper-retaining bail pivotally mounted to swing about a fixed axis parallel with the platen between "on" and "off" positions, of 85 means for yieldably holding the bail in both of said positions comprising an arm pivotally mounted to swing about an axis parallel with the bail axis and a helical tension spring anchored at its opposite ends to the bail and arm to directly exert a constant pull on said bail in a direction urging the bail toward "on" position, said bail having a portion against which said arm is yieldably pressed by said spring and shiftable longitudinally 90 of the arm, during movement of the bail from "on" to "off" position, from a point at which said constant direct pull of the spring on the bail is augmented by the thrust of the arm on said bail portion to a point at which 95 said direct spring pull is overcome by the thrust of the arm on the bail portion. 100

19. A typewriting machine as claimed in claim 18, wherein means are provided for positively limiting the throw of the bail, 105 and the spring is anchored to the bail at the side of the bail axis at which the bail cross-bar is located and anchored to the arm at a point to extend between the axes of the bail and arm in all positions of the bail, the bail portion engaged by the arm being located at the opposite side of the bail axis from that at which the spring is anchored to the bail. 110

In testimony whereof I hereunto affix my signature. 115
